Primary Examiner — Karen S Acker(74) *Attorney, Agent, or Firm* — Vorys, Sater, Seymour & Pease LLP(57) **CLAIM**

The ornamental design for a sheet material, as shown and described.

DESCRIPTION

FIG. 1 is a front elevational view of a design for a sheet material; and,

FIG. 2 is a front perspective view of the design as seen in FIG. 1.

The broken lines represent the boundary of the claim and form no part of the claimed design.
